UNITED STATES PATENT OFFICE.

JULIAN H. PITKIN, OF CHICAGO, ILLINOIS.

DIVISION-BLOCK FOR HAY-BALERS.

No. 813,665.

Specification of Letters Patent.

Patented Feb. 27, 1906.

Application filed October 23, 1905. Serial No. 283,923.

To all whom it may concern:

Be it known that I, JULIAN H. PITKIN, a citizen of the United States, residing at Chicago, in the county of Cook and State of Illinois, have invented a new and useful Improvement in Division-Blocks for Hay-Balers, of which the following is a complete specification.

This invention relates to division-blocks for balers; and it consists in certain improvements therein designed to better protect the engaging edges of the block from the severe usage which it generally receives from the retaining-springs. The transversely-extending grooves are effectually prevented from becoming injured and choked with hay at their ends, thus rendering easy the passing of the wires therethrough, and a large well-defined recess is provided to actuate the trigger on the block-alarm mechanism.

Referring to the accompanying drawings, Figure 1 represents an elevation of a division-block in which is embodied my invention, and Fig. 2 is an elevation of an edge thereof. Fig. 3 shows a perspective, on a reduced scale, of the block illustrated in the preceding figures. Fig. 4 represents an enlarged perspective of one of the reinforcing-plates, having formed integral therewith a recess for operating the trigger of the block-alarm; and Fig. 5 is a similar perspective of such reinforcing-plate without the recessed portion formed thereon.

In the drawings, 1 designates the vertically-extending center board, and 2 the side boards. Between the adjacent edges of the side boards are formed the oppositely-disposed transversely-extending grooves 3, through which the wires are made to pass in threading the machine, preferably three of these grooves being formed on each side of the block. To protect the ends of the side boards adjacent to the grooves from the bruising effect of the retaining-springs of the baler and to insure a normal sized opening at the ends of said grooves, the reinforcing-plates 4 are mortised into the edges of the block. These plates correspond in width with the thickness of the block and have depth and length sufficient to give them ample strength. In the sides of the reinforcing-plates are formed the notches 3', which

register with the transversely-extending grooves 3 and correspond therewith in cross-section. On the inner face of each plate is formed the vertically-extending grooves 5, adapted to receive the edge of the center board 1. The said plates are preferably secured in place by means of screws received by the apertures 6.

On the upper end of one set of the reinforcing-plates and formed integral therewith are the large recesses 7, the walls of which are made flush with the sides of the block. The function of this recess is to engage and actuate the trigger of the block-alarm. Heretofore in such devices the openings of the grooves through which the wires are threaded were depended upon to actuate the alarm-trigger, but owing to its small size they would often become clogged with hay and the alarm mechanism thereby rendered inoperative. With a large and independent recess the operation of the alarm mechanism is rendered more positive and efficient.

What I claim as my invention, and desire to secure by Letters Patent, is—

1. A division-block for hay-balers consisting of a center board having side boards secured thereto, with transversely-extending grooves between said side boards and reinforcing-plates arranged flush with the edge of said block, said reinforcing-plates having vertically-extending grooves which receive the edges of said center board, and transversely-extending notches which register with the grooves formed between said side boards, substantially as and for the purpose specified.

2. A division-block for hay-balers provided with transversely-extending grooves and having reinforcing-plates arranged flush with the edges of said block, said reinforcing-plates having notches therein registering with the said grooves, and a recess formed above the said notches, substantially as and for the purpose specified.

JULIAN H. PITKIN.
